Application March 27, 1945, Serial No. 585,128

11 Claims. (Cl. 64—25)

1

This invention relates to couplings, and more particularly to means for connecting two rotating members, such as parts of an internal combustion engine ignition system, so that angular adjustments of said parts may be automatically effected during rotation thereof, whereby the firing time of the spark producing means in the engine cylinders may be automatically varied.

One of the objects of the present invention is to provide novel apparatus for mechanically coupling two rotating members to each other while permitting of angular adjustment of one of said members relative to the other.

Another object of the invention is to provide a novel automatic variable coupling for rotating parts which functions in accordance with the speed of rotation of said parts.

A further object is to provide novel means for automatically effecting adjustments in the timing of the ignition system of an internal combustion engine.

Still another object is to provide novel coupling means of the above character whereby two rotating parts may be automatically angularly adjusted in one direction relative to each other at two different speeds of rotation, and in the other direction at a third speed of rotation.

A still further object is to provide a novel, centrifugally responsive device for effecting an automatic variable connection between two rotatable parts.

Another object is to provide novel means adapted for use in the ignition system of an internal combustion engine for effecting spark advance at one engine speed, and a retardation of the spark at engine speeds above and below said first speed.

Another object is to provide a novel ignition apparatus for an internal combustion engine whereby the sparks in the cylinders of the engine may be both advanced and retarded relative to the position of the pistons in said cylinders by a single, centrifugally actuated unit for coupling two rotating parts which are adapted for relative angular movement.

Another object is to provide coupling means of the above character which also functions to some extent as a flexible coupling to avoid damage which might otherwise be occasioned by sudden shocks and quick changes of speed.

The above and further objects and novel features of the invention will more fully appear from the following detail description when the same is read in connection with the accompanying drawings. It is to be expressly understood, however, that the drawings are for the purpose of illustration only, and are not intended as a definition of the limits of the invention, reference for this latter purpose being had primarily to the appended claims.

In the drawings, wherein like reference characters refer to like parts throughout the several views,

2

Fig. 1 is an end elevation, with portions of certain parts broken away, showing one form of the coupling unit comprehended by the present invention and associated with the magneto of an internal combustion engine;

Fig. 2 is a top plan view of the coupling unit shown in Fig. 1;

Fig. 3 is a vertical transverse section on the line 3—3 of Fig. 1;

Fig. 4 is a detail side elevation of the driven member of the coupling unit;

Figs. 5 and 6 are detail side elevations of the spark advancing and retarding levers, respectively, of the coupling unit; and

Fig. 7 is a detail side elevation of the driving member of the coupling unit.

Referring to the drawings, the present invention is herein illustrated, by way of example, in the form of a coupling unit adapted for use in the ignition system of an internal combustion engine. As shown, the novel coupling unit of the invention is associated with a magneto for the purpose of automatically varying the timing of the sparks in an ignition system relative to the positions of the pistons in the engine in which the sparks occur. The coupling unit is employed for connecting a rotating part of an engine (not shown) to the rotor shaft 10 in a magneto 11 which may be of any suitable design well known in the art. In a manner also well understood by those skilled in the art, the rotor of the magneto is drivably connected with a circuit breaker (not shown) which is synchronized with the rotor and determines the time of occurrence of the sparks in the engine cylinders. In a structure of this character wherein the timing cam is driven by or in timed relation with the magneto rotor, the coupling unit of the present invention is preferably located so that the rotor and the cam are affected alike by adjustments made by said unit, thereby insuring the opening of the primary circuit of the magneto coil at the most advantageous moment for efficient operation irrespective of the adjustments effected by the coupling unit.

As herein shown, the novel coupling means whereby shaft 10 is flexibly connected to an engine driven part for automatic, angular adjustment relative thereto, comprises two end members 12 and 13, and two intermediate force transmitting members 14 and 15. In a manner to be more fully described hereafter, these members are novelly mounted about shaft 10, and novel centrifugally responsive means, such as links 16, 17 and 18, are provided for drivably connecting end member 12 to end member 13 through the intermediate members 14 and 15.

For purposes of description, end member 12 may be considered as the driving member of the coupling unit since it is connected, although not necessarily, to the prime mover which, in the present instance, is a rotating part of an engine on which magneto 11 is mounted. As shown, driving member 12 is in the form of a lever hav-

ing an arm 19 which is offset to the right (Fig. 3) and extends in a radial direction from the axis of rotation of shaft 10. The hub 20 of member 12 is provided at one end thereof with external splines 21 adapted to engage an internally splined rotating part of the engine for imparting rotation to driving member 12 in a counter-clockwise direction as viewed in Fig. 1.

Driving member 12 is loosely mounted on the sleeve or hub 22 of end member 13, and for this and other purposes said hub is formed with a reduced portion 23 receiving and providing a bearing surface for driving member 12, and with a second reduced portion 24 adjacent portion 23 but of a diameter larger than the diameter of the latter. Hub portions 23, 24 provide shoulders or abutments 25 and 26 (Fig. 3), the shoulder 25 serving to hold driving member 12 against inward endwise displacement on hub 22, and to maintain said member in proper operating position.

End member 13, which may be conveniently referred to as the driving element of the coupling unit, is engaged over a smooth reduced portion of shaft 10, and is drivably connected to the latter by means of splines 27 (Fig. 4) within hub 22 that mesh with external splines 28 on said shaft (Fig. 3). Driven member 13 is in the form of a lever comprising the hub 22, and an arm 29 which is offset to the left (Fig. 3) and extends in a radial direction from the axis of rotation of shaft 10 in the same path of rotation as arm 19 of driving member 12.

The intermediate members 14 and 15 are arranged between the driving member 12 and the shoulder 26 on hub 22 of driven member 13, and are loosely mounted on the reduced hub portion 24 for free, angular movement relative to each other and to members 12 and 13. The intermediate member 14, which may be referred to as the spark advancing lever of the coupling unit, is formed with a radially extending arm 30 that is slightly offset to the left (Fig. 3) to lie in the same path of rotation as arms 19 and 29 of the driving and driven members 12 and 13, respectively. The intermediate member 15, which may be referred to as the spark retarding lever of the coupling unit, is formed with a radially extending arm 31 that is slightly offset to the right (Fig. 3) to lie in the same path of rotation as the arms 19, 29 and 30 of the members 12, 13 and 14, respectively.

The centrifugally responsive means 16 provided for operatively connecting members 12 and 14 comprises a link which is preferably fabricated from two arcuate plates 32, 32, each having riveted thereto on the outside and adjacent one end thereof a weight 33 (Figs. 1 and 2). Plates 32, 32 straddle the arms 19 and 30 of members 12 and 14, respectively, and are pivotally connected with the free end of arm 19 by a shouldered pin 34 which is journalled in said arm and projects beyond opposite sides thereof through said plates and has threaded on its opposite ends plate retaining nuts 35. Pin 34 acts as spacing means for plates 32, 32 and prevents binding of said plates on arm 19 upon tightening of nuts 35.

The opposite ends of plates 32, 32 which straddle arm 30 of member 14 are provided with suitable openings to receive the opposite ends of a shouldered pin 36 (Fig. 1) that extends through an elongated slot 37 in said arm and has journalled thereon an anti-friction roller 38. Pin 36 is identical in construction as pin 34 and has threaded on its opposite ends retaining nuts 39, said pin also serving as spacing means for plates 32, 32 and prevents binding of said plates on arm 30 upon tight-

ening of said nuts. Slot 37 extends generally in the direction of rotation of the coupling unit, and is of a curvature so that, when the centrifugally responsive means 16 is thrown outwardly, an angular movement will be imparted to intermediate member 14 relative to driving member 12. It will be understood that slot 37 may be given a variety of contours depending on the results desired. Connected at 40 to arm 19 of driving member 12 is one end of a pull spring 41 (Figs. 1 and 3) the opposite end of which extends between plates 32, 32 and is connected to a pin 42 carried by said plates. Spring 41 is under a predetermined tension when the above described parts are stationary for holding said parts in the positions illustrated, with roller 38 engaging the advance end of slot 37.

Centrifugally responsive means 17 are provided for drivably connecting intermediate member 14 to intermediate member 15, said means being the same as but having different operating characteristics than the connecting means 16 between members 12 and 14 heretofore described. As shown, means 17 comprises two arcuate plates 43, 43 (Figs. 1, 2 and 3) which extend on opposite sides of arms 30 and 31 of members 14 and 15, respectively, and have riveted to the outside and adjacent one end thereof weights 44, 44. Plates 43, 43 are pivotally connected with the advance end of arm 30 of member 14 by a shouldered pin 45 which is the same in construction as pin 34 and is journalled in a suitable opening 46 (Fig. 5) in said arm. Pin 45 projects beyond opposite sides of arm 30 through plates 43, 43 and has threaded on its opposite ends retaining nuts 47, said pin serving as spacing means for plates 43, 43 and prevents binding of the latter on arm 30.

The ends of plates 43, 43 adjacent arm 31 of member 15 are provided with suitable openings to receive the opposite ends of a shouldered pin 48 (Figs. 1, 2 and 3) which extends through an elongated slot 49 formed in said arm and extending generally in a radial direction from the axis of rotation of the coupling unit. Pin 48 has journalled thereon an anti-friction roller 50 disposed within slot 49, and has threaded on its opposite ends plate retaining nuts 51, 51, said pin also serving as spacing means for plates 43, 43, and prevents binding of the latter on arm 31 of member 15. Roller 50 is normally held against the inner end of slot 49 by suitable resilient means, such as a pull spring 52 having one end connected at 53 to arm 30 of member 14. The opposite end of spring 52 extends between plates 43, 43 and is connected to a pin 54 carried by said plates. For purposes to be described hereafter, spring 52 is of a predetermined tension but which is greater than the tension of spring 41.

Intermediate member 15 is drivably connected to the driven member 13 by the centrifugally responsive means 18 which is the same as but different in operation from both the connecting means 16 and 17 heretofore described. As shown, centrifugally responsive means 18 comprises two arcuate plates 55, 55 (Figs. 1 and 2) which extend on opposite sides of arms 29 and 31 of members 13 and 15, respectively, and have riveted to the outside and adjacent one end thereof weights 56, 56. Plates 55, 55 are pivotally connected to the free end of arm 29 of driven member 13 by a shouldered pin 57 which is the same in construction as pin 34 and is journalled in a suitable opening 58 (Fig. 4) in said arm. Pin 57 projects beyond opposite sides of arm 29 through plates 55, 55 and has threaded on its opposite ends retaining

nuts 59, said pin serving as spacing means for plates 55, 55 and prevents binding of the latter on arm 29.

The opposite ends of plates 55, 55 which straddle arm 31 of intermediate member 15 are provided with suitable openings to receive the opposite ends of a shouldered pin 60 (Fig. 1) which extends through an elongated opening 61 formed in said arm and extending generally in a radial direction from the axis of rotation of the coupling unit. Pin 60 has journaled thereon an anti-friction roller 62 disposed within slot 61, and has threaded on its opposite ends plate retaining nuts 63, 63, said pin also serving as spacing means for plates 55, 55 and prevents binding of said plates on arm 31 of member 15. Roller 62 is normally held against the inner end of slot 61 by resilient means, such as a pull-string 64 having one end connected at 65 to arm 29 of driven member 13. The other end of spring 64 extends between plates 55, 55 and is connected to a pin 66 carried by said plates. For purposes to be hereinafter described, spring 64 is of a predetermined tension but which is less than the tension of springs 44 and 52.

The driven member 13 is provided with stop means for purposes to be hereinafter described, said stop means being in the form of a bolt 67 which is adjustably threaded in the arm 29 of said member at the side thereof adjacent the driving member 12, and is locked in adjustable positions by a lock nut 68. Bolt 67 is preferably provided with impact cushioning means in the form of a fibre or rawhide plug 69 secured in the head of said bolt.

The above described various component parts of the coupling may be bench assembled in operative relation, and mounted on the rotor shaft 10 as a single coupling unit, said unit being held on said shaft by a nut 70 which is threaded onto the end of shaft 10 and either engages or effectively engages the outer end of the hub 22 of driven member 13. The inner end of hub 22 engages a shoulder on shaft 10, or a bearing surface on the housing of magneto 11. In order to insure free, angular relative movements of members 12, 13, 14 and 15, the driving member 12 is designed to be capable of having slight end-play on the hub portion 23 of driven member 13.

As hereinbefore described, the tension of spring 64 associated with the weight means 18 is lighter than the tension of spring 44 associated with the weight means 16 which, in turn, is lighter than the tension of spring 52 associated with the weight means 17, thereby controlling the speeds at which links 16, 17 and 18 are individually thrown outward by centrifugal forces acting on said weight means. With this understanding of the yielding capabilities of springs 64, 44 and 52, the operation of the coupling unit may be described as follows:

When the coupling unit is rotated in the counterclockwise direction, as viewed in Fig. 1, at a predetermined low speed, the various parts of the coupling unit occupy the positions shown in Fig. 1, and the engine is operated at one spark setting which in the present instance is an advance spark setting. As the engine speed is increased to a predetermined speed the centrifugal forces acting on each of the weight means 16, 17 and 18 at said speed is effective only on the weight means 18 and causes the latter to pivot counter-clockwise about pivot 57 against the tension of spring 64. The free end of said weight means 18 will then be swung outwardly as the

speed increases until roller 62 contacts the outer end of slot 61. The effect of the outward movement of weight means 18 is to shorten the connection between intermediate member 15 and driven member 13, thereby causing member 15 to move angularly in a counter-clockwise direction, as viewed in Fig. 1, relative to driven member 13 and shaft 10. Since during this functioning of weight means 18 there is no relative angular movement of members 12 and 15, the driven element 13 and rotor shaft 10 are effectively retarded with respect to driven member 12, thereby causing a retardation in the timing of the sparks in the engine cylinders relative to the positions of the pistons in said cylinders.

It will be understood that by properly designing the parts above described a variety of modes of operation may be obtained. If the relative angular positions of members 13 and 15 or, in the illustrated structure, spark retardation is plotted against the angular speed of member 12, the contour of the curve obtained may be greatly varied, for example, by changing the contour of slot 61, by changing the initial tension or design of spring 64, by changing the connecting points or other characteristics of the several parts so that the relationship between the increase in spring tension and the increase in effective centrifugal force, as weight means 18 moves outwardly, is changed, or by providing additional springs that come into play at different positions of weight means 18. The spark retardation or relative movement obtained may, for example, be either gradual or abrupt or it may be obtained in a series of abrupt or gradual steps.

When the engine speed is increased to a predetermined speed which is higher than that required to effect outward movement of weight means 18 in the manner described above, the centrifugal force acting on the weight means 16 causes the latter to pivot clockwise (Fig. 1) about pivot 34, and hence, move roller 38 as the speed increases outwardly toward the trailing end of slot 37 in intermediate member 14. This outward movement of roller 38 necessitates angular movement of intermediate member 14 in a counter-clockwise direction (Fig. 1) relative to driving member 12 since pivot 34 is nearer to the trailing end of slot 37 than it is to the advance end of said slot. Thus, driven member 13 since it is drivably connected to intermediate member 14 through the weight means 17, intermediate member 15, and weight means 18, is caused to move angularly in a counter-clockwise direction (Fig. 1), or ahead, relative to driving member 12 until the stop means 67 contacts the adjacent side of driving member 12, thereby effecting setting of the sparks to full advance position in the ignition system served by the magneto 11. Engagement of stop means 67 with driving member 12 limits the extent of outward movement of the centrifugally responsive means 16, and the resultant angular movements of members 14 and 13 relative to driving member 12, whereby full advance setting of the sparks is assured. It will be understood that any desired advance spark setting may be obtained by adjusting the stop means 67 relative to driven member 13, and that the outward movement of the centrifugally responsive means 16 and the resultant advance spark setting may be gradual or relatively abrupt, depending upon the design, connection and arrangement of the parts, and the contour of the slot 37, the same as explained above in connection with the centrifugally responsive means 18.

When the engine speed is increased to a predetermined speed which is higher than that required to cause outward movement of weight means 18 and 16 in the manner described above, the centrifugal force acting on the weight means 17 causes the latter to pivot clockwise (Fig. 1) about pivot 45 against the tension of spring 52. Under these conditions, the free end of weight means 17 will be swung outwardly as the speed increases until the roller 50 contacts the outer end of slot 49 in intermediate member 15. The effect of this outward movement of weight means 17 is to shorten the connection between intermediate member 14 and intermediate member 15, thereby causing members 12 and 14 to move angularly in a counter-clockwise direction, as viewed in Fig. 1, or ahead, relative to members 13 and 15. Since driving member 12 is advanced relative to driven member 13 during this functioning of weight means 17, the driven member 13 and rotor shaft 10 in effect are retarded with respect to driving member 12, thereby causing a second retardation of the sparks but at a higher engine speed as distinguished from the first retardation of the sparks effected by the centrifugally responsive means 18 at a somewhat lower engine speed.

As the angular speed of the parts is reduced to or slightly below the predetermined speeds at which weight means 16, 17 and 18 reach the outward limits of their movements, in the manner above described, springs 41, 52 and 64, respectively, return said weight means to their normal or illustrated positions, thereby reversing the relative angular movements of the parts and, hence, the movements of the weight means. Thus, an engine may, for example, be operated at an advanced spark setting for low speeds, at retarded and advanced spark settings for intermediate speeds, and at a retarded spark setting for high speeds, said spark settings being automatically effected by the apparatus of the present invention.

There is thus provided novel coupling means for rotatable parts, such as a magneto rotor and drive shaft therefor, whereby relative angular movements of said parts in either direction may be automatically effected during rotation thereof, and whereby relative angular movements in opposite directions may be effected as the speed of rotation increases. Additionally, said coupling means are so constructed as to effect different relative angular movements of the connected parts at predetermined speeds thereof in response to centrifugal forces. The coupling unit provided may be employed in a novel manner to automatically control the spark setting of an ignition system in an infinite variety of ways for the purpose of obtaining efficient and economical operation at substantially all speeds. Furthermore, the novel coupling means provided is simple in construction and operation and is also compact and reliable.

Although only one embodiment of the invention is illustrated and described in detail, it is to be expressly understood that the same is not limited thereto. As will now be apparent to those skilled in the art, various changes, such as in the design and arrangement of parts illustrated, may be made in the illustrated embodiment of the invention without departing from the spirit and scope thereof. For a definition of the limits of the invention, reference is had primarily to the appended claims.

What is claimed is:

1. Apparatus of the class described comprising a rotatable driving member, a rotatable driven member, and means drivably connecting said members whereby the latter rotate together and are adapted for limited angular movement relative to each other, said connecting means comprising two intermediate connecting elements mounted for angular movement relative to said members about the axis of rotation thereof and centrifugally responsive means operatively connected with said elements and with at least one of said members for effecting relative angular movements of said members in different directions in response to centrifugal forces acting on said responsive means as the speed of rotation increases.
2. Apparatus of the class described comprising at least two rotatable members adapted for limited angular movement relative to each other, and means for drivably connecting said members including two intermediate connecting elements angularly movable relative to each other and to both said members about a common axis, centrifugally responsive means connected to said elements and to said members and centrifugally responsive means connecting said elements for effecting relative angular movements of said members in different directions and an additional relative angular movement in one of said directions in response to centrifugal forces acting on said responsive means.
3. In apparatus of the class described, a rotatable driving member, a rotatable driven member, and means drivably connecting said members whereby the latter rotate together and are adapted for limited angular movement relative to each other, said connecting means comprising two intermediate elements movable angularly relative to each other and to both of said members, centrifugally responsive means pivotally mounted on said driving member, centrifugally responsive means pivotally mounted on said driven member, other centrifugally responsive means pivotally mounted on one of said intermediate elements, resilient means resisting movement of each of said centrifugally responsive means in response to centrifugal forces, and a pin and slot connection between said centrifugally responsive means and said intermediate elements.
4. Apparatus of the class described comprising at least two rotatable members adapted for limited angular movement relative to each other, and means for drivably connecting said members including two intermediate connecting elements angularly movable relative to each other and to both said members, centrifugally responsive means connecting said intermediate members, centrifugally responsive means connecting said driving members and one of said intermediate elements, and other centrifugally responsive means connecting said driven member and the other of said intermediate elements, two of said centrifugally responsive means being adapted to independently effect relative angular movement of said members in one direction in response to centrifugal forces and the other of said centrifugally responsive means being adapted to effect relative angular movement of said members in the other direction in response to centrifugal forces.
5. Apparatus of the class described comprising a rotatable driving member, a driven member mounted for rotation with and angular move-

ment relative to said driving member, each of said members having a radially extending arm, and means for operatively connecting said members comprising two intermediate elements each having a radially extending arm, said element arms and said member arms all being positioned to rotate in substantially the same path, and centrifugally responsive means pivotally mounted on each of said member arms and on one of said element arms and having cam connections with said elements whereby said centrifugally responsive means are effective to effect relative angular movement of said members in different directions at different speeds of rotation and to effect an additional relative movement of said members in one of said directions at another speed of rotation in response to centrifugal forces acting on said responsive means.

6. Apparatus of the class described comprising driving and driven rotatable members adapted for angular movement relative to each other, two intermediate torque transmitting elements movable angularly relative to each other and to both of said members, said elements and said members having radially extending portions adapted to rotate in substantially the same circumferential path, centrifugally responsive means operatively connecting the radially extending portions of said driving member and one of said elements, other centrifugally responsive means operatively connecting the radially extending portions of said driven member and the other of said elements, other centrifugally responsive means connecting the radially extending portions of both said elements, and resilient means for individually resisting movement of each said centrifugally responsive means whereby the latter become operative at different speeds of rotation of said members to effect relative angular movements of said members first in one direction, then in the opposite direction and thereafter in the first-named direction in response to centrifugal forces acting on said centrifugally responsive means as the speed of rotation of said members increases.

7. Apparatus of the class described comprising a rotatable driven member having a radially extending arm, a rotatable driving member loosely mounted on said driven member and having a radially extending arm, two intermediate elements loosely mounted on said driven member and each having a radially extending arm, all said arms being positioned to rotate in a common circumferential path, and means drivably connecting said members and adapted to effect angular movements of one of said members relative to the other of said members at different increasing speeds of rotation of said members, said connecting means comprising centrifugally responsive means pivotally mounted on said driving member and having a pin and slot connection with one of said intermediate elements, centrifugally responsive means pivotally mounted on said last-named element and having a pin and slot connection with the other of said intermediate elements, and centrifugally responsive means pivotally mounted on said driven member and having a pin and slot connection with said other intermediate element.

8. Apparatus of the class described comprising a rotatable driving member, a rotatable driven member, and means for drivably connecting said members while permitting relative angular movement thereof, said connecting means including a plurality of intermediate connecting

elements angularly movable relative to each other and to both said members about a common axis and a plurality of centrifugally responsive means operatively connected with said elements and with said members, one said centrifugally responsive means connecting one said member to one said element and being operative to effect relative angular movement of said members in one direction, another said centrifugally responsive means connecting the other said member to another said element and being operative to effect relative angular movement of said members in the other direction, and another said centrifugally responsive means connecting two of said elements and being operative to effect relative angular movement of said members in said one direction, said movements being effected in sequence as the speed of rotation of said members increases.

20 9. A coupling for aligned shafts comprising members projecting radially from and fixed to the shafts, a plurality of fulcrum arms interposed between the members, said arms being angularly movable relative to each other and to both said members about a common axis, and pivoted centrifugally responsive links joining each member to an arm and the arms to adjacent arms by connections that alter the angular relations of the members under the influence of the centrifugal forces induced by rotation of the shafts and operating said links.

35 10. A coupling for aligned shafts comprising members projecting radially from and fixed to the shafts, a plurality of fulcrum arms interposed between the members, said arms being angularly movable relative to each other and to both said members about a common axis, and pivoted centrifugally responsive links joining each member to an arm and the arms to adjacent arms by pin and slot connections that alter the angular relations of the members under the influence of the centrifugal forces induced by rotation of the shafts and operating said links, each of said links being responsive to different speeds of rotation than the other of said links.

45 11. A coupling for aligned shafts comprising members projecting radially from and fixed to the shafts, a plurality of fulcrum arms interposed between the members, said arms being angularly movable relative to each other and to both said members about a common axis, and pivoted centrifugally responsive links joining each member to an arm and the arms to adjacent arms by pin and slot connections that alter the angular relations of the members under the influence of the centrifugal forces induced by rotation of the shafts and successively operating said links, the latter being responsive to different speeds of rotation, one said link being operable at an intermediate speed to reverse the angular setting established by other said links operable at higher and lower speeds.
